A. MORPETH

SHADE ROLLER

Filed May 3, 1920

Inventor
Anthony Morpeth
By Frank E. Lorraine, Jr.
Attorney

UNITED STATES PATENT OFFICE.

ANTHONY MORPETH, OF MUSKEGON, MICHIGAN.

SHADE ROLLER.

Application filed May 3, 1920. Serial No. 378,504.

To all whom it may concern:

Be it known that I, ANTHONY MORPETH, a citizen of the United States of America, residing at Muskegon, in the county of Muskegon and State of Michigan, have invented certain new and useful Improvements in Shade Rollers; and I do hereby declare the following to be a full, clear, and exact description of the invention, such as will enable others skilled in the art to which it appertains to make and use the same.

This invention relates to curtain or shade rollers. It is particularly concerned with novel improvements in devices of this character, one of such improvements being directed to a means whereby the roller may be readily and quickly detached from the brackets which are usually made use of to carry the roller and at the same time not have to use the usual bracket with a slot therein cut downwardly from an upper edge of the bracket, the openings in the brackets at both ends of the roller being of a closed type which prevents any disengagement of the roller from the brackets due to upward movement of the roller with respect to the brackets. This is particularly useful in shade rollers used with motor vehicles having a closed car body, in which, if slotted brackets were used, there would be strong probability of disengagement of the shade rollers from shocks imparted in travel. A further novel feature of my invention resides in the construction of a metal shade roller having a hollow sheet metal body closed at its ends by metal plugs which are soldered in place, on one of which the usual holding dogs or pawls are mounted. It is very essential that these dogs or pawls be free to move at all times and to insure this, the plug carrying said pawls is made in a novel manner so that salts used in soldering cannot, under any circumstances, come to the pivotal mountings of the pawls and cause a corrosion which would destroy their free pivotal movement.

The invention by which these and other results not specifically set forth at this point are attained is illustrated in the accompanying drawing, in which,

Fig. 1 is a front elevation of a shade roller made in accordance with my invention.

Fig. 2 is an enlarged vertical longitudinal section taken through the shade roller.

Fig. 3 is a transverse section taken substantially on the line 3—3, of Fig. 2 and

looking in the direction indicated by the arrows, and

Figs. 4 and 5 are end elevations of the constructions shown in Fig. 1, illustrating particularly the supporting brackets for the roller.

Like reference characters refer to like parts in the different figures of the drawing.

The body 1 of the roller is a tube of metal 65 which is closed at its ends by plugs 2 and 3, each, preferably being equipped with a flange larger than the body of the roller as shown. The plug 2 at one end of the roller has a short tube 4 of metal attached thereto 70 and extends into the roller. A pin 5 passes loosely through the plug 2 and is formed with a head 6 larger in diameter than the opening through the plug, said head entering the tube 4. The inner end of the tube 75 4 is filled by a plug 7 soldered or otherwise permanently secured in the tube, and a coiled spring 8 is disposed between the head 6 of pin 5 and plug 7, the tendency of which is to keep the pin projected out as far as it 80 will go. However, by pressure against the end of the pin, it may be easily forced inwardly, as is obvious.

The portion 3^a of the plug 3 at the opposite end of the roller has an annular groove 85 9 cut in it entirely around the same. Pawls 10 are mounted on pins 11, the ends of which pass into the groove 9 where the same may be conveniently headed over to make a permanent connection. A rod 12 having a flattened outer end 12^a passes loosely through plug 3 and is provided with a slot 13 in position to be engaged by the dogs 10 in the usual manner in shade rollers. The inner end of the rod 12 enters and is connected to a metal tube 14 which extends to and seats at its inner end in a socket in a wooden piece 15 which is secured to and within the body 1 of the roller. A coiled spring 16 around the tube 14 and attached 90 to one end to the piece 15 serves to connect the rod 12 and tube 14 at its other end, hold the tube in its socket and act as a torsion spring to wind the shade on the roller in the usual manner with shade rollers. 95

Brackets 17 and 18 may be used to support the ends of the roller, the bracket 17 having an opening therein to receive the flattened end 12^a of the rod 12 and the bracket 18 a circular opening for the entrance of pin 5. 110 The roller is applied by inserting the end 12^a into the opening in bracket 17 and pin

5 is forced inwardly so that the end of the roller at which it is positioned may be brought into proper position with reference to bracket 18 after which the pin is released 5 and passes through the opening in the bracket. The removal of the roller is accomplished by pressing in on the pin 5 until it is disengaged from the bracket 18.

This construction obviates the necessity 10 of slotting bracket 17 to its outer edge for the entrance of the end 12° of rod 12, and thus insures against upward movement of the end of the roller at which rod 12 is mounted and disengagement of the roller 15 from the brackets such as may happen, particularly with motor vehicles equipped with shade rollers. At the same time, the roller is readily removed whenever desired or put in place between the brackets very readily 20 and quickly.

The plugs 2 and 3 are soldered into the ends of the body 1, in which operation, certain soldering salts and acids are used. Without the groove 9 on the plug 3, said 25 salts or acids pass along the plug and come eventually to the pawls 10 where they are loosely mounted on the pins 11, with a resultant corrosion which interferes with the free movement of the pawls. The groove 30 breaks the passage of said salts or acids to the pawls and insures against the possibility of such interference with the free movement of the pawls. This is a very necessary feature of the invention and the 35 construction, while simple, is particularly practical and efficient. In addition, the groove allows a ready access to the ends of the pins 11 for securing them in place against disengagement.

40 The constructions described have proven very practical and are used extensively. The invention is defined in the appended claims and I consider myself entitled to all 45 forms of construction which fall within the scope of the claims.

I claim:

1. A shade roller comprising a cylindrical body, a plug attached at one end of the body, said plug having an opening there- 50 through, a thin walled tube attached to the

plug and extending therefrom inwardly, a pin formed with an outer shank and an enlarged head only located with the head in the tube and the shank extending through the opening in the plug, a second plug closing the inner end of the tube, and a spring disposed between the head of the pin and said second plug, substantially as described. 55

2. A shade roller comprising a hollow elongated metal body, a plug inserted in one 60 end of the body, a rod passing through the plug, said rod being slotted in a side at a point within the body, pawls pivotally mounted on the inner end of the plug and pins passing through the pawls into the plug 65 to make said pivotal mount, said plug being soldered to the body and having a groove cut around the same to prevent passage of soldering materials to the pawls, and also providing means of access to the ends of the 70 pins for securing them on the plug, substantially as described.

3. A shade roller comprising a hollow elongated metal body, a plug having an annular groove cut around the same inserted 75 in one end of the body and soldered thereto, and pawls pivotally mounted on the plug at the inner end thereof, the pivot pins passing into the plug and to said groove, being headed in said groove to secure the pins on 80 the plug, substantially as described.

4. A shade roller comprising a cylindrical body, a plug attached to and closing one end of the body, said plug having an opening therethrough, a thin-walled metal tube attached to the plug at the inner side thereof and extending inwardly into the body of the roller, a pin comprising only a shank and an enlarged inner head located with the head in said tube and against the inner side of the 90 plug with the shank and extending loosely through the opening in the plug, said tube having a closed inner end, and a spring disposed between the closed end of the tube and the enlarged end of the pin, substantially as 95 for the purposes described.

In testimony whereof I affix my signature.

ANTHONY MORPETH.
